US0D1099311S

(12) **United States Design Patent** (10) **Patent No.:** **US D1,099,311 S**
(45) **Date of Patent:** **** Oct. 21, 2025**

(54) **BLOOD COLLECTION DEVICE**

(71) Applicant: **Medline Industries, LP**, Northfield, IL (US)

(72) Inventors: **Zachary Rzeszutek**, Chicago, IL (US); **Steven Bisbikis**, Northbrook, IL (US); **Connor Feeney**, Wilmette, IL (US)

(73) Assignee: **Medline Industries, LP**, Northfield, IL (US)

(**) Term: **15 Years**

(21) Appl. No.: **29/891,968**

(22) Filed: **May 11, 2023**

(51) LOC (15) Cl. **24-02**

(52) U.S. Cl.

USPC **D24/112**

(58) **Field of Classification Search**

USPC D24/112–114, 108, 127–131, 133, 186

CPC A61M 25/0606; A61M 25/0637; A61M 2039/062

CLAIM

The ornamental design for a blood collection device, as shown and described.

DESCRIPTION

FIG. 1 is a perspective view of a top side of a blood collection device;

FIG. 2 is a perspective view of a bottom side of a blood collection device;

FIG. 3 is an elevation view of the left side of a blood collection device;

FIG. 4 is an elevation view of the right side of a blood collection device;

FIG. 5 is an elevation view of the front side of a blood collection device;

FIG. 6 is an elevation view of the back side of a blood collection device;

FIG. 7 is a plan view of the top side of the blood collection device; and,

FIG. 8 is a plan view of the bottom side of a blood collection device.

The broken lines shown in FIGS. 1–8 illustrate portions of the blood collection device that form no part of the claimed design.

1 Claim, 8 Drawing Sheets
